STEAM GENERATOR

John Phillips Badenhausen, Philadelphia, Pa.

Application November 1, 1941, Serial No. 417,450

7 Claims. (Cl. 122—34)

This invention relates to steam generators, and more particularly to a steam generator in which steam at high pressure and temperature is utilized for generating steam at a lower temperature and pressure.

It is an object of the present invention to provide a steam generator, of the character aforesaid, in which adequate provision is made for superheating the steam generated therein.

It is a further object of the present invention to provide a steam generator, of the character aforesaid, in which the parts subjected to high pressure will require a minimum of material while retaining adequate strength.

It is a further object of the present invention to provide a steam generator, of the character aforesaid, in which the heating fluid at high pressure and the heated fluid at a lower pressure are kept separated so that contamination of the high pressure fluid is avoided.

It is a further object of the present invention to provide a steam generator, of the character aforesaid, with adequate provision for expansion and contraction of the parts thereof upon changes in temperature.

Other objects of the invention will be apparent from the annexed specification and claims.

The nature and characteristic features of the invention will be more readily understood from the following description, taken in connection with the accompanying drawing forming part hereof, in which:

Figure 1 is a vertical central sectional view through a preferred embodiment of the steam generator of the present invention;

Fig. 2 is a horizontal sectional view taken approximately on the line 2—2 of Fig. 1;

Fig. 3 is a horizontal sectional view taken approximately on the line 3—3 of Fig. 1;

Fig. 4 is a horizontal sectional view taken approximately on the line 4—4 of Fig. 1;

Fig. 5 is a fragmentary view, somewhat enlarged, of a portion of the structure shown in Fig. 2;

Fig. 6 is a fragmentary view, somewhat enlarged, taken approximately on the line 6—6 of Fig. 5; and

Fig. 7 is a view similar to Fig. 2 showing a modified form of the invention.

It will, of course, be understood that the description and drawing herein are illustrative merely, and that various modifications and changes may be made in the structure disclosed without departing from the spirit of the invention.

Referring more particularly to the drawing, in which a preferred embodiment of the invention is illustrated, an outer casing 10 is provided, preferably having an outer side wall 11, cylindrical in horizontal cross section, and dished upper and lower ends 12 and 13. The upper end 12 of the casing 10 is preferably provided with a plurality of manholes 14 for access to the interior.

Within the casing 10, an inner high pressure compartment 15 is provided, movable with respect to the casing 10 as hereinafter pointed out. The inner compartment 15 has an upper horizontal closure wall 16, consisting of a tube sheet, and spaced from the upper tube sheet and parallel thereto, a lower horizontal closure wall 17, consisting of a tube sheet. A cylindrical wall 18 extends between the tube sheet 16 and the tube sheet 17, and is disposed inwardly from the outer side wall 11 to provide a downflow space for the low pressure fluid. The upper wall 16 and the lower wall 17 are respectively secured in fluid-tight relationship at their peripheries to the cylindrical wall 18.

25 A central conduit 20 is provided, in communication with the interior of the compartment 15. The conduit 20 is secured to the lower dished end 13 of the casing 10 in fluid-tight relationship for supporting the compartment 15 and extends upwardly through the lower tube sheet 17 to which it is also secured in fluid-tight relationship. The upper end of the conduit 20 is spaced downwardly from the upper tube sheet 16 for permitting high pressure fluid flow into the interior space within the compartment 15.

30 35 Fig. 2 is a fragmentary view, somewhat enlarged, of a portion of the structure shown in Fig. 2;

Fig. 3 is a fragmentary view, somewhat enlarged, taken approximately on the line 3—3 of Fig. 1;

Fig. 4 is a fragmentary view, somewhat enlarged, taken approximately on the line 4—4 of Fig. 1;

Fig. 5 is a fragmentary view, somewhat enlarged, of a portion of the structure shown in Fig. 2;

Fig. 6 is a fragmentary view, somewhat enlarged, taken approximately on the line 6—6 of Fig. 5; and

Fig. 7 is a view similar to Fig. 2 showing a modified form of the invention.

It will, of course, be understood that the description and drawing herein are illustrative merely, and that various modifications and changes may be made in the structure disclosed without departing from the spirit of the invention.

Between the upper tube sheet 16 and the lower tube sheet 17, and in the space between the fluid conduit 20 and the compartment wall 18 a plurality of closely spaced and preferably staggered

tubes 28 is provided. The tubes 28 are connected to the tube sheets 16 and 17 in fluid-tight relationship, and the interiors of the tubes 28 are in communication with the space above the upper tube sheet 16 and the space below the lower tube sheet 17. These tubes 28 which may be of the order of two and one-half inch tubes, provide riser tubes for generation of steam or other vapor in the low pressure fluid.

Between the upper tube sheet 16 and the lowermost tube sheet 24, and in the space within the conduit 20, closely spaced and preferably staggered tubes 29 are connected to the tube sheets 16 and 24 in fluid-tight relationship, the interiors of the tubes 29 being in communication with a space 30 above the upper tube sheet 16, which space 30 is in communication with a steam collecting space 31 at the upper part of the casing 10. The interiors of the tubes 29 are also in communication with the connector 25 below the lowermost tube sheet 24. The tubes 29 may be of the order of one inch tubes.

The upper tube sheet 16 preferably has secured thereto in fluid-tight relationship an upwardly disposed tubular extension 32, which surrounds the space 30, and this extension 32 may be either circular, as shown in Figs. 1, 2 and 5, or polygonal, as illustrated in Fig. 7 at 32a. The normal water level is approximately as indicated at 33, and the extension 32 prevents the flow of water into the interior of the tubes 29. The inner compartment 15 is preferably connected to the casing 10, in a manner to permit of a slight sliding movement vertically therein, and for this purpose, sockets 34 secured to the inner face of the wall 11 of the casing 10 may be provided, and slides 35 carried by the wall 18 are also provided, and movable within the sockets 34. The inner compartment 15 is supported by the fluid conduit 20 and guided by the slides 35 and sockets 34, and may thus accommodate itself to the required position within the casing 10, in accordance with temperature conditions, without imposing undue strains on the casing 10 or the compartment 15.

The operation of the steam generator of the present invention will now be pointed out.

The water at low pressure is introduced through the low pressure inlet connection 26 into the space below the lower tube sheet 17, and passes upwardly within the interior of the tubes 28, wherein it is heated and vaporized into steam. A downpass for the low pressure water is provided between the wall 18 and the interior of the casing wall 11. The steam rises within the tubes and passes toward the upper part 31 of the casing 10. The steam in the uppermost part 31 of the casing 10 passes downwardly through the tubular extension 32 and then within the interiors of the tubes 29, wherein it is superheated. The superheated steam passes to the discharge connection 25 from which it is conducted to the place of use. The steam at high temperature and pressure which supplies the necessary heat and which may be at a pressure of the order of six hundred pounds per square inch, is introduced through the inlet connection 22 into the fluid chamber 23 within the downward extension 21. This high pressure fluid passes upwardly in counterflow and heat exchange relationship with the exteriors of the tubes 29 within the central conduit 20, thereby superheating the downflowing steam within the tubes 29, passes over the upper end of the conduit 20, and then downwardly in heat exchange relationship with the

exteriors of the tubes 28 extending between the upper tube sheet 16 and the lower tube sheet 17 for heating the water within the interiors of the tubes 28 and generating steam within the tubes 28. The steam delivered from the steam generator may thus be superheated and delivered for process use at a pressure of the order of 160 pounds per square inch. The high pressure fluid, in giving up its heat, is condensed, and the condensate is discharged through the discharge pipe 27.

The steam generator of the present invention is particularly adapted for use with a closed high pressure circuit which includes a high pressure steam generator from which steam is obtained for driving a turbine, and in which the high pressure steam, as delivered from the high pressure boiler, or as tapped from an intermediate stage of the turbine, is utilized as the supply of high pressure high temperature fluid for the lower pressure steam generator. The condensate in the high pressure circuit is then returned to the boiler for steam generation. In this manner, the water in the high pressure circuit, after initial treatment, is substantially free from scale forming properties, and may be continuously circulated in the high pressure circuit without subsequent contamination. The low pressure steam, generated out of direct contact with the high pressure steam, is available in adequate quantities for plant use at the lower pressures required for process use, and in a superheated condition to meet the process demands.

I claim:

1. In a steam generator, a casing having inlet and discharge connections for one fluid medium, said casing having a gaseous fluid collecting space therein, a compartment within said casing having tube sheets at the ends thereof and an inclosing wall connecting said tube sheets, steam generating tubes connecting said sheets within said wall, inlet and outlet connections for said compartment for the delivery of fluid heating medium into the interior of said compartment for contact with the exteriors of said tubes, the inlet connection for said compartment including a tubular member for supporting said compartment and extending inwardly therein and in communication with the interior of said compartment, superheating tubes in said tubular member in communication with said collecting space and said discharge connection for superheating the steam generated in said steam generating tubes.

2. In a steam generator, a cylindrical casing having inlet and discharge connections for one fluid medium and having a steam collecting space therein, a compartment within said casing having tube sheets at the ends thereof and a wall connecting said tube sheets, steam generating tubes within said wall connecting said sheets, an inlet connection for said compartment for the delivery of fluid heating medium into the interior of said compartment for contact with the exteriors of said tubes, said inlet connection including a tubular member extending inwardly and in communication with the interior of said compartment, a superheater tube sheet within said tubular member and superheating tubes in said tubular member in communication with said collecting space and said discharge connection for superheating the steam generated in said steam generating tubes, said superheating tubes terminating at one end at said superheater tube sheet.

3. In a steam generator, a casing having a steam collecting space at the upper part thereof

and fluid inlet and discharge connections, spaced upper and lower tube sheets within said casing, a wall connecting said tube sheets to provide a compartment within said casing, a conduit connected to said casing and closed at the lower end by a lowermost tube sheet, said conduit extending into and being in communication with the interior of said compartment, steam generating tubes connecting said lower and upper tube sheets, steam superheating tubes connecting said upper and said lowermost tube sheets, and connections for supplying heating fluid to the interior of said compartment for contact with the exteriors of said tubes.

4. In a steam generator, a vertically disposed casing having a steam collecting space at the upper part thereof and fluid inlet and discharge connections, spaced upper and lower tube sheets within said casing, a wall connecting said tube sheets to provide a compartment within said casing, a conduit carried by said casing and extending into the interior of said compartment, a lowermost tube sheet for closing the lower end of said conduit, steam generating riser tubes connecting said lower and upper tube sheets, said wall being spaced from said casing to provide a downward circulating fluid path, steam superheating downflow tubes within said conduit connecting said upper and said lowermost tube sheets and in communication with the steam collecting space, and connections for supplying fluid to the interior of said compartment for contact with the exteriors of said tubes.

5. In a steam generator, a vertically disposed cylindrical casing having a steam collecting space at the upper part thereof and fluid inlet and discharge connections, spaced upper and lower tube sheets within said casing, a cylindrical wall spaced inwardly within said casing and connecting said tube sheets to provide a compartment within said casing, a conduit connected to the lower portion of said casing and extending upwardly through said lower tube sheet and in communication with the interior of said compartment, a lowermost tube sheet for closing the lower end of said conduit, steam generating riser tubes connecting said lower and upper tube sheets, steam superheating tubes in said conduit con-

necting said upper and said lowermost tube sheets and in communication with the steam collecting space, and connections for supplying heating fluid to the interior of said compartment for contact with the exteriors of said tubes.

6. In a steam generator, a vertically disposed cylindrical casing having a steam collecting space at the upper part thereof and low pressure fluid inlet and discharge connections, spaced upper and lower tube sheets within said casing, a cylindrical wall spaced inwardly within said casing and connecting said tube sheets to provide a high pressure compartment within said casing, a conduit connected to the lower portion of said casing and extending upwardly through said lower tube sheet and in communication with the interior of said compartment, a lowermost tube sheet for closing the lower end of said conduit, steam generating riser tubes connecting said lower and upper tube sheets, steam superheating tubes in said conduit connecting said upper and said lowermost tube sheets and in communication with the steam collecting space, and connections for supplying high pressure heating fluid to the interior of said compartment for contact with the exteriors of said tubes.

7. In a steam generator, a vertically disposed cylindrical casing having a steam collecting space at the upper part thereof and low pressure fluid inlet and discharge connections, spaced upper and lower tube sheets within said casing, a cylindrical wall spaced inwardly within said casing and connecting said tube sheets to provide a high pressure compartment within said casing, a central conduit for supporting said compartment and in communication with the interior of said compartment, a lowermost tube sheet for closing the lower end of said conduit, steam generating tubes connecting said lower and upper tube sheets, steam superheating tubes in said conduit connecting said upper and said lowermost tube sheets and in communication with the steam collecting space, connections for supplying high pressure heating fluid to the interior of said compartment for contact with the exteriors of said tubes, and sliding connections between the wall of said compartment and said casing.

JOHN PHILLIPS BADENHAUSEN.
